TOBACCO PIPE

Harold G. Wyse, Dayton, Ohio

Application December 22, 1939, Serial No. 310,482

3 Claims. (Cl. 131—195)

This invention pertains to tobacco pipes and more particularly to a cooling and condensing unit interposed in the pipe stem.

The desire of every pipe connoisseur is for a dry, cool, sweet smoke. In the use of an ordinary tobacco pipe the smoke vapors and other products of combustion reach the mouth of the smoker in a more or less heated condition, accompanied by moisture extracted from the tobacco intermixed with saliva previously deposited in the pipe stem and frequently distastefully flavored by nicotine extract and tar compounds freed from the tobacco charge by combustion.

In the present instance, the products of combustion are conducted through a tortuous passage of sufficient length to effect radiation of the heat and condensation of entrained moisture and extractives, which are collected and segregated before reaching the pipe bit in the mouth of the smoker. As a result, the smoke drawn from the mouth piece, or bit, is comparatively cool and uniformly dry, with no objectionable flavor.

A primary object of the invention is to provide a radiator condenser pipe which may not only be economically manufactured, but will be more efficient in use, uniform in its operation, having relatively few parts and unlikely to get out of repair.

A further object of the invention is to provide a pipe of the character described of conventional shape and compact construction capable of being easily and quickly assembled and disassembled for cleaning.

A further object of the invention is to eliminate the strong soggy heel which forms in the bottom of the bowl of a conventional pipe, thus enabling complete combustion of the charge and minimizing tobacco waste.

A further object of the invention is to provide a smoke from which objectionable extractives have been eliminated and hence free from tongue bite.

A further object of the invention is to provide rapid and efficient heat transfer from the pipe parts to atmosphere by combined conduction, radiation, and convection.

A further object of the invention is to enable the trapping of all tobacco particles and moisture.

A further object is to provide a pipe structure wherein the radiator condenser unit is readily accessible and may be quickly disassembled for cleaning and thereafter reassembled.

A further object of the invention is to provide a smoking pipe having the advantageous

structural features and inherent meritorious characteristics hereinafter described.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawing.

In the drawing, wherein is shown the preferred but obviously not necessarily the only form of embodiment of the invention,

Fig. 1 is a perspective view of the assembled pipe.

Fig. 2 is a longitudinal sectional view thereof showing the condenser unit in position, and the location of the four condensation chambers. For illustrative purposes the several conductor tubes are illustrated in a common plane, whereas in practice they are offset as in Figs. 4 and 5.

Fig. 3 is a perspective view of the condenser unit removed from the assembly.

Fig. 4 is a cross sectional view on the line 4—4 of Fig. 2.

Fig. 5 is a cross sectional view on the line 5—5 of Fig. 2.

Fig. 6 is a side elevation of a cigarette holder in which the invention is embodied.

Like parts are indicated by similar characters of reference throughout the several views.

In the accompanying drawing there is shown a pipe of conventional shape, including the bowl 1, stem 2, and bit 3. The stem 2 includes a medially perforate tubular section 4 interconnected with the bowl 1 by an interposed fin carrying coupling 5.

The fin carrying coupling 5 has thrust engagement in the bottom of the bowl 1 and at its opposite end in the imperforate extremity 4a of the perforate section 4 and has therethrough a bore 6 connecting the interior of the bowl 1 with the imperforate extremity of the section 4. The perforate section 4 and fin carrying coupling 5 are preferably, although not necessarily, formed of metal. Because of its high heat conductive characteristics, aluminum is the preferred but not necessarily the only suitable material.

Located within the perforate section 4 is a radiator and condenser unit comprising three thin walled condenser tubes 7, 8, and 9, and end or terminal plugs 10 and 11. The end plugs 10 and 11 are each recessed to provide moisture collecting chambers 12 and 13. The radiator con-

denser unit is of less length than the perforate tubular section 4, affording within the imperforate terminals 4a thereof intermediate the plugs 10 and 11, and coupling 5, and the bit 3 respectively, supplemental collecting chambers 14 and 15.

The tube 7 connects the initial collecting chamber 14 beyond the plug or head 10, to which smoke is admitted from the bowl, with the second collecting chamber 13 in the opposite plug or head 11. Tube 8 is relatively short and interconnects chambers 13 and 12, in the respective plugs 10 and 11. Tube 9 connects chamber 12 in the plug 10 with the supplemental chamber 15 beyond plug 11 for discharge of cooled smoke to the bit 3. The perforate section 4 is counter-bored to provide a shoulder stop 16, against which the end plug 11 abuts to insure proper positioning of the condenser unit within the perforate tube 4 to provide the supplemental chambers 14 and 15.

The radiator condenser unit is so constructed that it may be easily disassembled for cleaning. The tubes 7 and 9 extend through the chambers 12 and 13 and terminate flush with the outer surfaces of the end plugs 10 and 11, respectively. Tube 8 is located at the top of the unit, as shown in Figs. 4 and 5, and is accessible for cleaning from either chamber 12 or 13.

The smoke passes through a tortuous path of travel in reverse directions and through a succession of spaced condensation and particle deposit chambers, in such path of travel. The smoke drawn through the bore 6 of the coupling 5 passes into chamber 14 where all the tobacco particles drawn from the bowl 1 and the initial condensation of moisture are trapped. The smoke then passes through tube 7 into chamber 13, where the moisture condensed during the passage through the tube is trapped. The direction of flow is then reversed and the smoke passes through tube 8 to chamber 12 where further moisture condensation is trapped. The smoke again flows in the opposite direction through tube 9 to the chamber 15 where the final condensate is trapped, and from where the dry, cool smoke is drawn through the bit 3. The chamber 13 also serves to trap any saliva that may enter the pipe, or if not removed in this chamber, it will be collected and held by the succeeding chambers. Any moisture within the pipe stem is prevented from entering the bowl of the pipe thus the tobacco in the bottom of the bowl is always dry and sweet and may be smoked to the very bottom with no harsh or irritating effects.

The heat generated by the burning tobacco and carried through the pipe stem by the smoke is dissipated in three ways, namely, by conduction, by radiation, and by convection. The coupling 5 rapidly and efficiently conducts the heat of combustion from the bowl 1 directly to the perforate tubular section 4. Heat is dissipated to the atmosphere by direct radiation from both the tube and the coupling fin. The end plugs 10 and 11 conduct heat directly to the tubular section 4 from which it radiates to the atmosphere. The heat of the smoke passing through the condenser tubes 7, 8 and 9 is transferred to the outer surfaces of the tubes by conduction, and then carried away from the tubes by convection. The perforations in the tubular section 4 permit circulation of natural convection air currents therethrough, whereby there is a continuous circulation of air around the tubes.

The tubular section 4 in addition to its heat transfer function serves as a guard or protective housing for the radiator condenser unit, preventing damage to the tubes, and preserving the conventional lines or shape of the pipe. In conjunction with the coupling 5 and bit 3 it defines the deposite chambers 14 and 15. The perforate tubular section 4 therefore serves a multi-functional purpose.

10 While the invention has been described in its application to a pipe, it is to be understood that it is equally applicable to a cigarette holder, as is shown in Fig. 6. Such construction is identical with that previously described with the exception that the cigarette receptacle 1a, the equivalent of the bowl 1, is disposed in axially aligned relation instead of being disposed in right angle relation. It is therefore to be understood that the term "pipe" as herein employed is to be deemed generically inclusive of the cigarette holder embodiment, and that the terminal receptacle 1a of Fig. 6 responds to the term bowl as employed in the claims.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A tobacco pipe, the stem of which includes a perforate tubular section connected at one end with the pipe bowl and at the other end with the pipe bit, a pair of relatively spaced heads located in imperforate terminal portions of the tube in spaced relation with the bowl connection and with the bit, deposit chambers in the respective heads, additional deposit chambers formed beyond the respective heads intermediate the bowl connection and the bit, a plurality of radiator tubes connecting the respective deposit chambers at each end of the tubular section beyond the respective heads with the chambers within the heads at the opposite ends of the tubes, an additional tube interconnecting the chambers within the respective heads one with the other, the construction and arrangement being such that there is provided a tortuous passage between the bowl and the bit, including a plurality of interconnected deposit chambers connected in sequence, the imperforate terminal portions of the perforate tube defining a part of each deposit chamber, the interconnecting conduits of which are exposed to circulation of atmospheric air.

2. A tobacco pipe or the like comprising a bowl, a stem and a bit, said stem including a perforate tubular sleeve having imperforate terminals, a plurality of condenser tubes, a pair of relatively spaced cylindrical heads interconnected by the

tubes, transverse bores in the cylindrical heads open at their ends and communicating one with the other through a portion of the tubes, others of said tubes communicating directly with only one of said bores and extending entirely through the opposite cylindrical head transversely of the bore therein, a pair of deposit chambers within the imperforate terminals of the sleeve exteriorly of the cylindrical heads with which the last mentioned tubes communicate, and communicating with the bowl and bit respectively, the construction and arrangement being such that the perforate sleeve surrounds the assembly and the imperforate terminals of the sleeve enclose the cylindrical heads, closing the transverse bores therein and extending beyond said heads to form the deposit chamber within the imperforate terminals of the sleeve between the cylindrical heads and the bowl and bit respectively.

3. A tobacco pipe or the like comprising a bowl, a stem and a bit, said stem including a perforate tubular sleeve having imperforate extremities, a plurality of condenser tubes, a pair of relatively spaced cylindrical heads interconnected by the tubes, transverse bores in the cylindrical heads open at their ends and communicating one with the other through a portion of the tubes, others of said tubes communicating directly with only one of said bores and extending entirely through the opposite cylindrical head transversely of the bore therein into communication with the bowl and bit respectively, the stem being so constructed and arranged that the perforate sleeve surrounds the assembly and the imperforate extremities of the sleeve enclose the cylindrical heads and close the transverse bores therein.

HAROLD G. WYSE.
